UNITED STATES PATENT OFFICE.

CHARLES H. PURDY, OF MICHIGAN CITY, INDIANA, ASSIGNOR OF ONE-HALF
TO HENRY W. JOHNSON, OF SAME PLACE.

ROTARY CHAIR.

SPECIFICATION forming part of Letters Patent No. 426,323, dated April 22, 1890.

Application filed August 3, 1889. Serial No. 319,693. (No model.)

To all whom it may concern:

Be it known that I, CHARLES H. PURDY, a citizen of the United States, residing at Michigan City, in the county of La Porte and State 5 of Indiana, have invented a certain new and useful Improvement in Rotary Chairs, which is fully set forth in the following specification, reference being had to the accompanying drawings, in which—

10 Figure 1 represents a vertical central section, and Fig. 2 a plan view, of the chair with the seat and spindle attached thereto removed.

15 My invention relates to that class of rotary chairs and stools which can be raised and lowered, so that the seat can be adjusted to any desired height; and my invention relates to the devices which enable me to revolve the seat without raising or lowering it, and also 20 raise or lower the seat by turning the seat-supporting device.

It also relates to the above-named devices, in combination with a ball-bearing, all constructed and operated as hereinafter fully 25 set forth.

In the accompanying drawings, A represents the chair or tool seat.

B is a block so connected to the seat as to turn with it. I have shown the block B attached rigidly to the seat A in the drawings, 30 which would be the simplest construction in revolving stools; but in constructing rotary chairs—such as office-chairs—the block B would be connected with the seat A, either 35 by springs or other well-known devices used in rotary office-chairs, but always so connected that the block B would revolve with the seat A. The block B is provided with a spindle C, as shown in the drawings.

40 D is an annular bearing-plate, which supports the entire weight that rests on the seat A, and is provided with a hollow shank or spindle E, through which the spindle C passes, and in which the spindle C has a contact-bearing at or near its ends. The shank or spindle E also has an exterior screw-thread F, which engages with an interior screw-thread in the nut G, which is rigidly connected to the legs H of the chair or stool.

45 I is a V-shaped groove in the bearing-plate

D, and J is a correspondingly-annular V-shaped groove in the block B.

K are hardened metal balls of the required size to fit in the V-shaped grooves I and J and prevent the block B from coming in contact with the plate D, but at the same time allow them nearly to touch, so that very little dust will reach the balls K.

The entire weight of persons sitting on the seat A rests on the balls K, which are supported upon the annular plate D. The balls K, resting in the V-shaped grooves I and J, prevent the entire side strain produced in moving the chair from being thrown upon the spindle C, and as the seat A is revolved the 60 balls K roll in the grooves I and J, and the spindle C turns in its bearing without the seat being raised or lowered.

When it is desired to raise or lower the seat, the person takes hold of the hand-wheel 70 L and revolves the plate D, with its hollow shank or spindle E, when, by means of the screw-threads F, the bearing-plate D will be raised or lowered, the seat A being correspondingly raised or lowered.

75 The hand-wheel L may be provided with suitable projections or handles for turning the annular plate D as desired.

In the operation of my invention a person sitting upon the seat A can turn about without raising and lowering the seat, as in ordinary revolving stools or chairs. The seat is revolved readily and held in a firm position on account of the balls K supporting the seat, as above specified. By reaching around beneath the seat the person can turn the supporting-plate D with its screw-threaded cylindrical shank and raise and lower the seat to any desired position.

80 M are pins put through the end of the spindle C to hold the seat in position upon its supports when the chair or stool is lifted to be moved about.

Having thus fully described the construction and operation of my invention, what I 85 claim as new, and desire to secure by Letters Patent, is—

1. In a revolving chair or stool, the interiorly screw-threaded nut or block G, to which the legs are attached, the bearing D, provided 90

with an exteriorly screw-threaded hollow shank having a smooth interior, and a spindle C, having a smooth exterior, fitting loosely in the hollow shank and rigidly connected to the seat for raising and lowering the seat without turning it, substantially as and for the purposes specified.

2. In a revolving chair or stool, the seat A, block B, attached to the seat and provided with the spindle C, and an anti-friction ball-bearing, the bearing D, provided with an

anti-friction ball-bearing and an exteriorly threaded hollow shank E, anti-friction balls K, and the interiorly screw-threaded nut or block G, for raising or lowering the seat without rotating it or rotating the seat without raising or lowering it, all constructed substantially as and for the purposes specified. 15

CHARLES H. PURDY.
